(57) **CLAIM**

The ornamental design for a video box, as shown and described.

DESCRIPTION

FIG. 1 is a perspective view of a video box showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a partially enlarged view of FIG. 1;

FIG. 10 is another partially enlarged view of FIG. 1;

FIG. 11 is a third partially enlarged view of FIG. 1;

FIG. 12 is a forth partially enlarged view of FIG. 1;

FIG. 13 is a partially enlarged view of FIG. 2;

FIG. 14 is another partially enlarged view of FIG. 2;

FIG. 15 is a third partially enlarged view of FIG. 2;

FIG. 16 is a partially enlarged view of FIG. 3;

FIG. 17 is a partially enlarged view of FIG. 5;

FIG. 18 is another partially enlarged view of FIG. 5;

FIG. 19 is a partially enlarged view of FIG. 6; and,

FIG. 20 is a partially enlarged view of FIG. 8.

The broken lines represent areas of enlargement and form no part of the claimed design.
